PENNSYLVANIA

INTERNAL-COMBUSTION-ENGINE PISTON

Application filed June 20, 1927. Serial No. 199,913.

The invention is an improvement in pistons for internal combustion engines and means for constructing the same whereby the efficiency of internal combustion engines in which our invention is embodied will be materially increased.

The duty of a bi-metallic piston is to perform the duty of a conventional all iron or all aluminum piston in such a manner that they will have none of the inherent disadvantages of pistons made of one metal. In the all aluminum piston the excessive expansion and excessive skirt wear do not permit the engine to perform at its highest efficiency. In the case of the all iron piston with its insufficient heat conduction and its excessive weight the compression ratio and high speed are greatly retarded. As the tendency in modern engine design is toward high speed and high compression ratios, it is seen that a piston light in weight with high heat conductivities must be used. A bi-metallic piston with the proper metal in the head section and shell or skirt section will eliminate the disadvantages of the single metal piston and when properly constructed will have none of their disadvantages.

It is the object of our invention to fulfil these exacting requirements by the construction of our shell to prevent expansion, and prevent the shell going out of round, by the forces exerted and to allow the shell to conform to the shape of the cylinder wall at all times. It is a further object to securely lock the two metals together and to use an aluminum or an aluminum magnezium alloy in the head section, so that it may have high heat conductivity.

Other objects and advantages flowing from the utilization of our invention will doubtless present themselves as the description proceeds and we would have it clearly understood that we reserve unto ourselves all rights to the full range of equivalents, both in manner of practicing our method or process and its use, to which we may be entitled under our invention in its broadest aspect.

For a consideration of what we believe to be novel in our invention, attention is directed

to the accompanying description and claims appended thereto.

We shall now proceed to describe our invention with reference to the accompanying drawings, wherein we have illustrated certain preferred embodiments for the purpose of presenting a clear and comprehensive disclosure, it being obvious that our invention is susceptible of taking other forms without departing from the scope and spirit thereof.

Fig. 1 is an elevation, in section, taken through the head, shell and wrist pin boss showing the manner of extending the shell beyond the inset wall to act as a reenforcement.

Fig. 2 is an elevation, in section taken through the head and shell section showing the manner of extending the shell metal beyond the inset wall to act as a reinforcement.

Fig. 3 is an elevation, in section taken through the head and shell section, showing the manner of reenforcing the inset wall and shoulder by the addition of shell metal.

Fig. 4 is an elevation, in section, taken through the head and shell section showing the manner of reenforcing the inset wall in the same manner as shown in Fig. 1.

Fig. 5 is an elevation, in section, taken through the head and shell section, showing the shell section constructed in two pieces.

Fig. 6 is an elevation, in section, taken through the head and shell section, showing the method of reenforcing the shoulder section by means of a ring.

Fig. 7 is an elevation, in section, taken through the head and shell section, showing the manner of constructing the shell section in two pieces.

Fig. 8 is an elevation, in section, taken through the head and shell section, showing the relieving of the shell section adjacent to the head section to allow for expansion of a shell with no additional reenforcement.

Fig. 9 is an elevation of a shell, in section, showing the shoulder reenforcement and lock holes.

Fig. 10 is an elevation of a shell, in section, showing the shoulder reenforcement and lock holes and a slot in the shell wall to

allow for shell to conform to any irregularities in the cylinder walls.

- Referring now to the drawings in detail in which like characters of reference are employed to designate similar parts throughout the several views, 2 is a piston skirt consisting of a thin high cast ferrous or non-ferrous skirt with a shoulder or inset wall 3 cast integral with a shoulder 4 with lock holes 8, shown in Figs. 1, 2, 3, 4, 6, 8, 9, 10 and reenforced by an integrally cast ring 5, to allow the shell section to resist the expansion forces due to the head section and prevent cracking or distortion of the shell section. In Fig. 6 10 the reenforcing ring 6 is a separate piece fitted over the shoulder section. This also prevents cracking or distortion of the shell section. In Fig. 5 is shown the shell constructed of two pieces, the skirt section 2 or 15 lower shell section with its integral cast wall 3 and shoulder section 7 with lock holes 8 and outwardly turned flange 9. The two pieces are attached in a convenient manner before the head is cast in place.
- 20 In Fig. 7 is shown the shell section 2 with inwardly turned flange 3 and attached to the inwardly turned flange is outwardly turned flange 10 of shoulder 11 having lock holes 8.

- In Fig. 8 is shown the shell 2 with integral- 30 ly cast wall 3 and shoulder 4 with lock holes 8. This construction has a relief at 12 adjacent to the head section which permits the shell 2 to distort in the vicinity of the inset wall 3 where no additional reenforcement is 35 added to the shoulder construction.

- The head and shell sections are interlocked by allowing the head section metal to flow through holes 8. In Fig. 10 slot 3 allows the shell to have flexibility that it may conform 40 to the irregularities of the cylinder wall.

14 are compression ring grooves and may be of any number to suit the various conditions in engine construction.

- It is seen that in some instances it may be 45 desirable to modify the number or shape of reenforcing rings. It is also seen that the number of lock holes or their shape may be modified to meet different conditions. It is also seen that the shape or the direction of the 50 slot and the number of slots may be modified as can the relief at the shoulder section.

We claim:

1. In a bi-metallic piston, a cast iron shell having portions of major and minor diameters with a connecting surface in a horizontal plane, said surface projecting inwardly of the inner face of the shell wall to form an internal circumferential ledge between the two portions of different diameters, the wall 55 of said shell above said horizontal surface being apertured, and a head of an aluminum alloy cast upon said shell, the metal of said head extending through said apertures and about said connecting surface and its internal projection.

2. In a bi-metallic piston, a cast iron shell having portions of major and minor diameters with a connecting surface in a horizontal plane, said major portion being apertured to receive a wrist pin and having an 70 inturned flange at its lower end, said connecting surface extending inwardly to form an internal circumferential reinforcing ledge of lesser diameter than that of the shell, the wall of said portion of minor diameter being 75 apertured, and a head of an aluminum alloy with integral wrist pin bosses coinciding with said wrist pin apertures in the shell, cast upon said shell, said head metal extending through said apertures in the portion of 80 minor diameter and entirely embracing said portion of minor diameter, the inner surface of said head metal coinciding with the inner surface of said reinforcing ledge.

3. A cylindrical cast iron shell for a bi- 85 metallic piston, having a relatively thin uniform wall section and formed with a portion of reduced diameter at its upper end, forming a circumferential shoulder, said reduced portion being provided with apertures, said shoulder extending inwardly from the inner surface of said portion of reduced diameter to form an internal circumferential ledge.

4. A cylindrical shell for a bi-metallic piston of cast iron, having a relatively thin wall 95 section apertured to receive a wrist pin, with an inturned flange at its lower end, and formed with a portion of reduced diameter at its upper end of uniform wall section, providing a circumferential shoulder, said reduced portion being provided with horizontally disposed elongated circumferentially spaced apertures, said shoulder extending inwardly beyond the inner surface of the reduced portion to form a circumferential re- 100 105 inforcing ledge for said shell.
